(57) **CLAIM**

The ornamental design for a magnetic sign holder, as shown and described.

DESCRIPTION

FIG. 1 is an upper perspective view of the magnetic sign holder showing my design.

FIG. 2 is a front elevation view thereof;

FIG. 3 is a back elevation view thereof;

FIG. 4 is a side elevation view thereof;

FIG. 5 is an opposite side view thereof;

FIG. 6 is a top plan view thereof;

FIG. 7 is a bottom plan view thereof; and,

FIG. 8 is another upper perspective view thereof, showing an open position of a tab portion.

The back surface as shown in FIG. 3 is magnetic.
